UNITED STATES PATENT OFFICE.

WILLIAM ROSS, OF MONTREAL, QUEBEC, CANADA.

GRIZZLY FOR ORE SEPARATION.

1,332,305.

Specification of Letters Patent.

Patented Mar. 2, 1920.

Application filed June 7, 1919. Serial No. 302,373.

To all whom it may concern:

Be it known that I, WILLIAM Ross, a subject of the King of Great Britain, and resident of the city of Montreal, in the Province of Quebec, Canada, have invented certain new and useful Improvements in Grizzlies for Ore Separation, of which the following is a specification.

This invention relates to what are commonly known as grizzlies, that is, coarse screens formed of horizontal bars connected together and traveling in a closed orbit. In using such screens much trouble is caused by pieces becoming wedged between the bars, and by fine material which falls through the upper bars falling on the lower bars and collecting there. Apparatus to overcome this difficulty is described and shown in my co-pending application No. 270589 filed January 10th, 1919, and the object of the present invention is to devise apparatus which will possess the advantages of that set forth in the application referred to, which will operate at greater speed, and which may be readily arranged to classify the material into more than two products.

I attain my object by means of the constructions hereinafter described and illustrated in the accompanying drawings in which—

Figure 1 is a side elevation, partly broken away and partly in section, of a grizzly constructed in accordance with the present invention;

Fig. 2 a plan view of the same;

Fig. 3 a side elevation of a simple form of the invention;

Fig. 4 a partial cross section showing more particularly the means for vertically adjusting the supporting tracks of one of the sets of grizzly bars;

Fig. 5 a side elevation of part of a grizzly showing a modification of the form of the grizzly bars; and

Fig. 6 a side elevation illustrating more or less diagrammatically an arrangement of grizzly bars for classifying material into more than two products.

In the drawings like numerals of reference indicate corresponding parts in the different figures.

Referring particularly to Fig. 3, 1 are the main grizzly bars suitably carried by disks 2. These disks are also adapted to support a chain 3, to the links of which are secured

the intermediate grizzly bars 4. In the drawings, the disks are shown as notched to receive the bars 4, so that the spacing of the main and intermediate bars is always accurately maintained.

The chain 3 is of a length greater than the circumference of the circle intersecting the axes of the main grizzly bars. Consequently, at the under side the intermediate grizzly bars fall away from and hang below the main bars, so that the horizontal spacing between the bars at the under side of the grizzly is twice that at the upper side, thus facilitating the discharge of the fine materials passing through the upper part of the grizzly.

The preferred arrangement is shown in Figs. 1 and 2. In this form both the main and intermediate grizzly bars are carried by chains, and the chains are supported on two sets of sprocket wheels to cause the bars to move in an elongated orbit with its major axis substantially horizontal.

5—5 are shafts, each carrying two pairs of sprocket wheels 6 and 7. On the sprocket wheels 6 run the chains 8 carrying the main grizzly bars 1, while on the sprocket wheels 7 run the chains 3 carrying the intermediate grizzly bars 4. One or both of the shafts 5 may be driven as may be deemed desirable.

Supporting means are provided for the chains 3 and 8 between the sprocket wheels. The supporting means comprise tracks 9 and 10 suitably supported on the frame of the apparatus and engageable by anti-friction rollers 11 secured to the grizzly bars. The tracks for one set of bars at least are preferably given an undulated or serrated upper surface so as to cause a vertical vibration of the bars, which is particularly useful in the screening of wet or sticky material, which is liable to clog the apparatus. Preferably the tracks which are so undulated are arranged so that they may be brought into or out of action. When such tracks are

out of action, the supporting of all the bars at the upper part of the apparatus falls on the chains of the bars which are so supported, but these are always amply strong to take the added load.

In the drawings, I show the outer tracks 10 as vertically adjustable, being secured to sleeves 12 sliding on vertical rods 13 secured to the frame and threaded for engagement by the adjusting nuts 14. By

adjusting these nuts vertically, the tracks may be brought into or out of their operative position.

When it is desired to classify into more than two sizes, I adopt the design shown in Fig. 6 in which is shown a third set of grizzly bars 15 carried by sprocket wheels 16 suitably journaled and positioned so that the bars 15 alternate with the bars 1 and 4 adjacent the receiving end of the grizzly. As the orbit of the bars 15 is considerably shorter than the orbit of the other bars, close spacing is obtained adjacent the feed end of the grizzly and a wider spacing adjacent the discharge end, while ample increase of spacing between the bars at the under sides of their orbits is obtained.

Two separate discharge hoppers 17 and 18 are in this case required. In the other forms a single discharge spout 19 is provided. In all forms a feed spout 20 is employed and a tailing spout 21.

Preferably, the grizzly bars are round as indicated in most of the figures of the drawings, but flanged constructions such as shown in Fig. 5 may under some circumstances be employed. It will also be understood that more than three grades of product may be obtained by further extending the principle of construction illustrated in Fig. 6.

What I claim as my invention is:—

1. In a grizzly, the combination of substantially horizontal main grizzly bars adapted to be moved in a closed substantially vertical orbit and intermediate grizzly bars connected independently of the main bars and also adapted to be moved in a closed substantially vertical orbit larger than the orbit of the main bars, said orbits being substantially co-incident for part at least of their upper sides.

2. A grizzly constructed substantially as set forth in claim 1 in which the intermediate bars are carried by a pair of suitably supported chains.

3. A grizzly constructed substantially as set forth in claim 1 in which the main and the intermediate bars are carried by two pairs of separate suitably supported chains.

4. A grizzly constructed substantially as set forth in claim 1 provided with two spaced axles, two pairs of sprocket wheels on each axle, two pairs of separate chains supported on the sprocket wheels and to which the main and intermediate grizzly bars are respectively connected, and sup-

porting means for the ends of the bars when the latter are in the upper parts of their orbits.

5. A grizzly constructed substantially as set forth in claim 1 provided with two spaced axles, two pairs of sprocket wheels on each axle, two pairs of separate chains supported on the sprocket wheels and to which the main and intermediate grizzly bars are respectively connected, and supporting means for the ends of the bars when the latter are in the upper parts of their orbits undulated to cause a vertical vibration of one or both sets of bars.

6. A grizzly constructed substantially as set forth in claim 1 in which the orbits of the main and intermediate grizzly bars coincide for substantially the full length of their upper sides and which is provided with a third set of grizzly bars movable in a smaller orbit than either the main or intermediate bars and co-inciding with said orbits for a portion only of their upper sides.

7. A grizzly constructed substantially as set forth in claim 1 provided with two spaced axles, two pairs of sprocket wheels on each axle, two pairs of separate chains supported on the sprocket wheels and to which the main and intermediate grizzly bars are respectively connected, independent supporting means for the ends of the two sets of bars when the latter are in the upper parts of their orbits, the supporting means for one set of bars being undulated to cause a vertical vibration of one set of bars.

8. A grizzly constructed substantially as set forth in claim 1 provided with two spaced axles, two pairs of sprocket wheels on each axle, two pairs of separate chains supported on the sprocket wheels and to which the main and intermediate grizzly bars are respectively connected, independent supporting means for the ends of the two sets of bars when the latter are in the upper parts of their orbits, the supporting means for one set of bars being undulated to cause a vertical vibration of one set of bars, and means for raising and lowering the last mentioned supporting means to bring them into or out of action.

Signed at Montreal this 26th day of April 1919.
